United States Patent

Des. 241,177
Patented Aug. 24, 1976

241,177

DISK STORAGE UNIT OR SIMILAR ARTICLE

Bernard T. Cournoyer, Holden, and David M. Wright
and Jerome M. O'Toole, Shrewsbury, Mass., assignors
to Barry Wright Corporation, Watertown, Mass.

Filed Mar. 7, 1975, Ser. No. 556,199

Term of patent 14 years

Int. Cl. D3—99; D9—99; D14—99
U.S. Cl. D87—1 D

FIG. 2

FIG. 1

FIG. 3

FIG.4

FIG.5

FIG. 1 is a front elevation of a disk storage unit or similar article showing our new design;

FIG. 2 is a top plan view thereof;

FIG. 3 is a bottom plan view thereof;

FIG. 4 is a rear elevation thereof; and

FIG. 5 is a side elevational view thereof, the side not shown being a mirror image thereof.

We claim:

The ornamental design for a disk storage unit or similar article, as shown and described.
